UNITED STATES PATENT OFFICE.

GEORGE BROUGHAM HUBERT AUSTIN, OF ARMADALE, VICTORIA.

MECHANISM FOR ASSISTING IN PROPULSION OF CYCLES.

SPECIFICATION forming part of Letters Patent No. 633,943, dated September 26, 1899.

Application filed August 1, 1898. Serial No. 637,417. (No model.)

To all whom it may concern:

Be it known that I, GEORGE BROUGHAM HUBERT AUSTIN, architect, a subject of the Queen of Great Britain, residing at No. 60 Armadale road, Armadale, near Melbourne, in the British Colony of Victoria, have invented Improved Mechanism for Assisting in the Propulsion of Cycles, (for which I applied for a patent in Victoria on the 18th day of May, 1898, No. 15,203; in New South Wales on the 20th day of May, 1898, No. 8,377; in Queensland on the 21st day of May, 1898, No. 4,418; in South Australia on the 19th day of May, 1898, No. 5,395; in Tasmania on the 24th day of May, 1898, No. 2,168; in New Zealand on the 26th day of May, 1898, No. 10,619, and in Western Australia on the 25th day of May, 1898, No. 2,064,) of which the following is a specification.

This invention has been devised in order to utilize the cyclist's weight for assisting in the propulsion of the machine, especially on rough roads, where the rider is bumped up and down, or when mounting, or when it is practicable for the cyclist to raise or lower himself upon the saddle at intervals—as, for instance, when ascending hills.

According to my invention a tube or rod connected to the saddle extends for a considerable distance into one or more of the downwardly-projecting tubes of the frame of the machine and is provided near its lower end with suitable mechanism adapted to engage with gearing on or leading to the crank-shaft or hub of the drive-wheel, so as to utilize the movement of the rider on and off the saddle for the ultimate purpose of rotating said drive-wheel and so assisting in the propulsion of the machine. Suitable roller or other guides are provided for insuring said tube or tubes moving freely in the downwardly-projecting tubes of the frame, and the seat or saddle may in some cases be mounted in such a way that it can turn horizontally for a certain distance upon a pivot, thus lessening the chances of straining the mechanism.

Referring to the accompanying drawings, Figure 1 represents a central vertical section of the upper portion of the main down-tube of a bicycle fitted with my invention. Fig. 2 is a central vertical section of the lower part

of the device and designed to match with Fig. 1.

A represents an ordinary saddle carried by a pillar or support a , fitted into a short tube a' , mounted in ball-bearings a^2 within a larger tube B, extending nearly to the bottom of a downwardly-projecting tube C of the machine.

The tube B is provided near its top with a cross-pin b , extending diametrically across said tube, its ends being projected into slots b^x in the tube B. These slots b^x are formed horizontally or at right angles to the axis of the tube B and are comparatively short, as shown in Fig. 3, their length being such as to permit the saddle A to turn horizontally with the movement of the rider's body instead of permitting the strain of such movements to be communicated to the mechanism with which the lower end of the tube B is connected. At the top of the downwardly-extending tube C is a cap c' , and at the top of the tube B is a second cap b' . These two parts combine with the cross-pin b to hold the saddle A in proper position and prevent it from being removed by drawing the post a out of the tube a' . A clamping-collar a^3 fits around the upper end of the short tube a' , by means of which the height of the saddle may be adjusted.

D represents a locking-bolt adapted to engage with a hole in the tube B when it is desired to throw my auxiliary driving mechanism out of operation—for instance, when descending hills.

The tube B fits comparatively loosely into the downwardly-projecting tube C, but is kept in position and prevented from turning around by means of one or more removable rollers b^3 , working in one or more slots b^4 in said tube, as illustrated, with or without anti-friction guide-wheels b^5 , mounted on said tube. A spring B' is coiled around said tube B and always tends to lift said tube upward.

At the bottom of the tube B is a buffer. This buffer comprises a piston F, operating within a short cylindrical chamber F' at the bottom of the down-tube C, said chamber having an inlet-valve, as F^2 , an outlet-valve, as F^3 , and a pipe F^4 , leading into any suitable reservoir G for compressed air—such, for instance, as one or more of the tubes consti-

tuting the frame of the machine. On the downstroke of the piston F the air in chamber F' is forced into pipe F⁴ through outlet-valve F², and on the upstroke of said piston more air is drawn into chamber F' through inlet-valve F², and so on.

The tube B has a rack B², (see Fig. 2,) engaging with studs or cogs on a wheel D, mounted loosely on the crank-shaft and carrying pallets or pawls D², adapted to rotate a pinion E, keyed to the crank-shaft E', on the downward motion of the tube and escape on the upward movement as before.

The air forced into the reservoir G or into the tubes of the frame may be utilized for the blowing of a whistle or other signal, and the pressure might be relieved by an automatic relief-valve or other contrivance, which, however, it is not thought necessary to describe.

In operating the device the rider should rest his weight upon the pedals after the saddle has gone down in order to allow the coiled spring and buffer to return the saddle to its initial position, as will be readily understood.

Having now particularly described and ascertained the nature of my said invention and in what manner the same is to be performed, I declare that what I claim is—

In a mechanism for the propulsion of cycles, the combination with the drive-wheel shaft of a gear loosely mounted thereon, a ratchet rigid on said shaft, a pawl pivoted on said gear and meshing with the ratchet in one direction of movement, a saddle-supporting tube longitudinally movable in a part of the frame of the cycle and provided with a rack to mesh with the gear, an air-chamber below the shaft of said gear, a pipe leading from said chamber for connection with a storage-reservoir having a relief-valve, a piston upon the lower end of the movable tube to fit and have movement in said air-chamber, and inlet and outlet valves for the latter, substantially as described.

GEORGE BROUGHAM HUBERT AUSTIN.
